UNITED STATES PATENT OFFICE

JOHN A. MORRISON, OF WARREN, OHIO, ASSIGNOR, BY MESNE ASSIGNMENTS, TO WALKER MANUFACTURING COMPANY, OF RACINE, WISCONSIN, A CORPORATION OF WISCONSIN

LIFTING JACK

Application filed February 18, 1929. Serial No. 340,930.

The invention relates to jacks of the type used for raising automobiles, trucks, busses and the like and more particularly to a jack having a plurality of lifting members in order to provide a considerable lifting range.

The object of the improvement is to provide a jack having a hollow base within which is mounted a tubular lifting member, means being provided for raising this tubular member to the desired height, a lifting screw or other lifting member being movably mounted within the tubular member and provided at its upper end with a head for engagement with any desired portion of the vehicle to be lifted, means being provided for raising and lowering said lifting screw relative to the tubular lifting member.

A further object of the improvement is to provide a pawl or dog of peculiar construction for holding the tubular lifting member at any desired height and for preventing the same from being withdrawn entirely from the base.

A still further object is the provision of a removable top plate for the tubular lifting member, the same acting as a guide bearing for the lifting screw.

The above, and other objects which will be apparent from the following description, may be attained by constructing the improved lifting jack in the manner illustrated in the accompanying drawings, in which

Figure 1 is a side elevation of the lifting jack to which the invention pertains, showing the same adapted for use upon trucks, busses and other heavy vehicles, parts being broken away for the purpose of illustration;

Fig. 2, a section taken substantially on line 2—2, Fig. 1;

Fig. 3, a view similar to Fig. 2 of a modified form of the jack especially adapted for use upon lighter vehicles;

Fig. 4, a plan sectional view taken as upon the line 4—4, Fig. 3;

Fig. 5, a detached plan view of the top plate for the tubular lifting member; and

Fig. 6, an edge elevation of the same.

Similar numerals refer to similar parts throughout the drawings.

Referring first to the form of jack illus-

trated in Figs. 1 and 2, which is especially adapted for lifting heavy vehicles such as trucks, busses and the like, the jack comprises generally the substantially tubular base 10, the tubular lifting member 11 mounted for vertical movement in the base and the lifting screw 12 mounted for vertical movement in the tubular member.

The base 10 is preferably in the form of a malleable casting having the base plate 13 cast integrally with the tubular standard 14, and preferably reinforced as by the skirt flanges 14.

For the purpose of raising the tubular member 11, with reference to the base, rack teeth 15 may be formed longitudinally upon one side thereof for engagement with the pinion 16 preferably made integrally with the shaft 17 which is journaled through an integral housing 18 formed at the upper bottom portion of the base.

The shaft of this pinion may be provided with a socket similar to the socket 19 for connection with the usual jack operating handle.

In order to hold the tubular member 11 at any desired height, with reference to the base, ratchet teeth 20 may be formed upon the side of the tubular member for engagement with a pawl 21 carried by the base, the lowermost tooth 20a being of considerably greater depth than the remaining teeth in order to cooperate with the pawl 21 as a stop to limit the upward movement of the member 11 and prevent the same from being entirely disengaged from the base.

The pawl 21 is bifurcated as at 22 and rests upon the saddle 23 cast integrally with the ears 24 upon the base, the outer furcation 25 being extended downward for some considerable distance and preferably curved outward at its lower end as at 26, providing an operating handle for the pawl which may be engaged by the foot or by the usual jack operating handle to withdraw the upper end of the pawl from engagement with the ratchet teeth.

A coil spring 27 is seated in a socket 28, formed in the side of the base, between the ears 24, and engages the depending handle portion 25 of the pawl to normally urge the same to the position shown in Fig. 2, holding

the upper end of the pawl in engagement with the rack teeth 20.

Thus, as the pinion 16 is rotated to raise the tubular member 11, the pawl 21 will ride over 5 the rack teeth 20, dropping into position beneath each tooth after riding over the same, whereby the tubular member may be held in the desired raised position.

The upper end of the tubular member is 10 provided with an integral housing portion 29 having a preferably inclined tubular bearing portion 29a communicating therewith.

A combined nut and bevel gear 30 is housed 15 within the housing 28, a ball race 31 being provided in the lower peripheral portion thereof for taking the thrust.

The bevel gear teeth 32 thereon mesh with a bevel pinion 33 upon the shaft 34 journaled 20 within the bearing portion 29a, the socket 19 being fixed to the outer end of said shaft for receiving the usual operating handle.

The lifting screw 12 is threaded through the internal threads 36 of the combined nut and bevel gear and provided at its upper end with 25 a lifting head 37 for engagement with any desired portion of the vehicle to be lifted.

In order to provide a guide bearing for said screw and to permit easy access to the interior 30 of the housing 28, a detachable top plate 39 is provided upon the housing, having the central guide bearing portion 40 to receive the screw.

This top plate is shown in detail in Figs. 5 and 6 and may be provided around its periphery with a plurality of triangular lugs 41 35 for engagement in the notches 42 formed at the upper open end of the housing 28, each of these notches terminating in a triangular portion 43 to receive the triangular lugs 41 when 40 the top plate is turned to the closed or locked position.

For the purpose of easily turning the top plate to the locked or unlocked position, one or more bosses 44 may be provided upon the 45 upper surface thereof for engagement with any suitable implement.

In the operation of the jack, as above described, when it is desired to lift a vehicle, the jack, with the tubular member 11 and 50 lifting screw 12 in lowered position, is placed beneath the spring, axle, or other portion of the vehicle adapted to be engaged by the lifting head.

The usual jack operating handle is then 55 engaged with the socket of the pinion 16 and the pinion is rotated thereby to raise the tubular member 11 until the lifting head 37 substantially engages the portion of the vehicle to be lifted.

The tubular member will be held in this raised position by means of the pawl 21 and the operating handle is then connected with the socket 19, and the pinion 33 is rotated in 60 a proper direction to raise the screw 12 until

the vehicle has been raised to the desired height.

In lowering the jack, after the lifting screw has been lowered through opposite rotation 70 of the pinion 33, the tubular member 11 may be lowered by depressing the handle portion 25 of the pawl sufficiently to disengage the same from the ratchet teeth 20, the weight of the tubular member and screw being sufficient to lower the same by gravity. 75

In the form of the jack shown in Figs. 3 and 4, which is especially designed for comparatively light vehicles such as pleasure cars and the like, all parts of the jack are substantially as above described excepting 80 that the rack teeth 15 and pinion 16 are eliminated, spring means being provided in place of the same for automatically raising the tubular member 11a when the pawl 21a is released. 85

A spring barrel 45 is formed integrally with the standard 10a of the base, the axis thereof being parallel to the axis of the standard 10a.

A coil spring 46 is housed within this barrel, the lower end thereof resting upon the base plate 18a and the upper end engaging an ear 47 formed upon the side of the tubular member 11a. 90

The spring 27a, which controls the pawl, is 95 sufficiently strong to hold the pawl in engagement with the rack teeth 20', against the pressure of the spring 46.

The operation of this jack is the same as that above described, excepting that when the 100 pawl 21a is released from the ratchet teeth, the spring 46 will raise the tubular member 11a until the lifting head engages the vehicle to be lifted. The lifting screw may then be raised in the manner above described 105 to lift the vehicle to the desired height.

It will be obvious from the above that the improved jack provides a considerable lifting range and may be easily operated by the usual jack operating handle after the jack has been placed in position beneath the vehicle to be lifted. 110

The jack shown in Figs. 1 and 2 may be pushed into the desired position beneath the vehicle by means of the usual operating handle, after which first the pinion 16 and later the bevel pinion 33 may be in turn operated by the same operating handle. 115

The form of jack shown in Fig. 3 may in 120 the same manner be pushed to the desired position beneath the vehicle by means of the usual operating handle which may then be used to release the pawl 21a, permitting the spring 46 to raise the tubular member 11a to the desired position. 125

The operating handle may then be used as above described to raise the lifting screw.

I claim:

1. A lifting jack including a standard, a 130 tubular member movable longitudinally

within the standard, a lifting screw carried by the tubular member, rack teeth upon the tubular member, a rack-engaging pinion mounted upon the standard, ratchet teeth 5 upon the tubular member peripherally spaced from said rack teeth, a bifurcated pawl pivotally mounted on the standard and engaging the ratchet teeth to hold the tubular member in adjusted position, and an enlarged tooth upon the bottom of the tubular member below said ratchet teeth for coacting with said pawl to limit the upward movement of said tubular member.

2. A lifting jack including a standard, a 15 tubular member movable longitudinally within the standard, a lifting screw carried by the tubular member, rack teeth upon the tubular member, a rack-engaging pinion mounted upon the standard, ratchet teeth 20 upon the tubular member peripherally spaced from said rack teeth, a bifurcated pawl pivotally mounted on the standard and engaging the ratchet teeth to hold the tubular member in adjusted position, and means upon the 25 bottom of the tubular member below said ratchet teeth for coacting with said pawl to limit the upward movement of said tubular member.

In testimony that I claim the above I have 30 hereunto subscribed my name.

JOHN A. MORRISON.
